(57) **CLAIM**

The ornamental design for a telescopic support pole, as shown and described.

DESCRIPTION

FIG. 1 is a perspective view for a telescopic support pole, showing our new design;

FIG. 2 is a front view thereof;

FIG. 3 is a rear view thereof;

FIG. 4 is a side view thereof; and,

FIG. 5 is a front view of the telescopic support pole, in an extended configuration thereof.

The broken lines show portions of the telescopic support pole which form no part of the claimed design.
